UNITED STATES PATENT OFFICE.

MARIUS METHILTUS SØRENSEN, OF VALLERÖD, NEAR RUNGSTED, DENMARK.

PULLING-OVER MACHINE FOR BOOTS AND SHOES.

1,382,564.

Specification of Letters Patent. Patented June 21, 1921.

Application filed July 12, 1919. Serial No. 310,444.

To all whom it may concern:

Be it known that I, MARIUS METHILTUS SØRENSEN, a subject of the King of Denmark, residing at Vallerød, near Rungsted, 5 isle of Sealand, in the Kingdom of Denmark, have invented certain new and useful Improvements in Pulling-Over Machines for Boots and Shoes, of which the following is a specification.

- 10 The present invention relates to improvements in pulling-over machines for boots and shoes, and especially for footgear that is to be lasted according to the method of lasting described in my previous U. S. Patent No. 1224229 wherein a piece of wire is arranged to form a loop and is connected for instance, to the lower edges of the upper and the end portions of the wire crossed and then passed and secured at the top of the last.
- 15 The object of the invention is to provide a machine of the above character wherein the construction is improved, the number of parts comparatively few, the cost of production low and the efficiency high.
- 20 The invention is clearly illustrated in the accompanying drawings in which:—

Figure 1 is a plan view of the invention.

Fig. 2 is a transverse vertical sectional view thereof, and

- 30 Fig. 3 is a longitudinal vertical sectional view of the invention, the same being taken at right angles to the view shown in Fig. 2.

The machine has three gripping members, or pulling-over grippers, namely, stationary grippers 4, intended to grasp the toe-part of the upper, said grippers having a movable jaw 40, and the two pairs of grippers 5 and 6, which are, as a rule, movable in a vertical direction, and which are intended to grasp the corresponding side of the upper, having movable jaws 50 and 60, respectively.

The opening and shutting of the jaws 40, 50 and 60, and the pulling movement of the grippers 5 and 6, are caused by a member in common for both actions, preferably a pedal 7. This is, by means of a rod 8, connected with a slide 9, which is guided in the stationary gripper shank 4, and which with a roller 10, presses against the arm 41 of the movable jaw 40. Furthermore, the pedal 7 is, by means of a rod 11 and a cross-piece 14, connected with slides 12 and 13, which are guided in the corresponding gripper-shanks 5 and 6, and with corresponding rollers 15

and 16, press against the respective arms 51 and 61 of the movable jaws 50 and 60. These arms have such a shape that the jaws are turned shut when the slides 12 and 13 are moved downward a certain distance from the position shown in Figs. 2 and 3, after which the rollers enter into hook-shaped projections 52 and 62 at the base of the arms, so that the further downward movement of the slides is thereby transmitted to the closed grippers. The arm 41 has a similar shape, but without the hook-like projection. Instead of this, it has a straight prolongation 42 which, when the jaw 40 has been closed, assumes a position parallel to the moving direction of the slide-piece 9. Thus the roller 10, after the closing of the jaw, will be able to move downward still farther, thereby holding the jaw in the closed position. The arms 41, 51 and 61 act as counter-weights, which open the jaws when the actuation of the rollers 10, 15, and 16 ceases.

The grippers 4, 5, and 6 are placed on a table 17, which is the top-plate in a box-shaped frame 18, from whose front side the pedal 7 projects. The grippers 4 are disposed in a tubular standard 19 on a slide 20 in such a manner that it can be adjusted both in height and also at a greater or lesser distance from the grippers 5 and 6. In accomplishing the vertical adjustment of the grippers 4 in the tubular standard 19, a bolt 9' is screwed in the slide 9 and is arranged in a vertical slot 19' in the sleeve. A nut 20' is mounted on the projecting outer end of the bolt 9' and is designed for frictional engagement with the standard so as to maintain the slide in the desired position of vertical adjustment. Similarly for the horizontal adjustment, the slide 20 to which the standard 19 is fixed is provided with a longitudinal slot 21' through which is arranged a bolt 22' carried by the table 17. A nut 23' is engaged with this bolt for clamping the slide in the desired position of adjustment. To permit of the horizontal movement of the slide alining oblong slots 28' of a length equal to that of the slot 21' in the slide are formed in the slide and the table. For the grippers 5 and 6 there are provided guides 21 and 22, below the table 17, which guides are borne by slides 23 and 24, which by means of a suitable member, such as a right and left threaded screw 25,

may be adjusted at various distances from each other.

Between the grippers 5 and 6, there is a support 26 with a rest 27 for the last during the pulling-over process. The support is pivoted in a fork 28 and may be adjusted at greater and lesser distances from the grippers 4 or the standard 19, by means of an adjustable distance gage 29. The rest 10 27 is provided with a downwardly projecting extension in the form of a threaded bolt 27' which is keyed as at 30 in a cylindrical recess 28' in the support 26 and on the bolt is engaged the nut 30' which in 15 turn rests on the support 26. By turning the said nut on the bolt 30' the rest 27 may be lifted or lowered as desired.

Thus the situation of tongs and support may be adjusted according to the different 20 sizes and shapes of boots and shoes.

The movement of the pedal 7 may be limited by means of a stop 31. To make the pull from the treadle 7 to the tongs 5 and 6 resilient, springs 32, 33 and 34 may 25 be inserted, as shown in Fig. 3.

In using the machine, the toe and side parts of the upper placed on the last are placed in the open jaws 4, 5 and 6, which then, while the last is supported on the rest 30 27, are closed by the actuation of the pedal and, by continued pressure on same, the pulling-over is effected.

The shown and described details may without altering the nature of the invention 35 be modified in many different ways.

I claim:—

1. A pulling-over machine consisting of a support for the last, members for gripping the side parts of the upper, members for gripping the toe-part of the upper, arms 40 on the first-named gripping members having hook-shaped engaging elements, means for actuating these arms, first closing the gripping members and then moving them in the direction of the pulling-over by actuating said engaging elements, an arm on the gripping members for said toe-part having a straight prolongation, means for actuating this arm to close the gripping members and for holding them closed by following said straight prolongation, and a common moving member for said means. 45

2. A pulling-over machine consisting of a support for the last, movable members for gripping the side-parts of the upper, 50 members for gripping the toe-part of the upper, said gripping members being adjustable toward said support and an adjustable distance gage between said support and said gripping members for the 55 toe-part of the last, said support being adjustable toward and from the latter gripping members. 60

In testimony whereof I affix my signature in the presence of two witnesses.

MARIUS METHILTUS SØRENSEN.
